UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,571, dated September 26, 1899.

Application filed August 18, 1899. Serial No. 727,709. Term of patent 14 years.

To all whom it may concern:

Be it known that I, JEREMIAH A. SCRIVEN, a citizen of the United States, residing in the borough of Manhattan, city, county, and State 5 of New York, post-office address No. 18 East Fifteenth street, in said city, have invented and produced a new and original Design for Bifurcated Nether Garments, of which the following is a specification.

10 The leading feature of my invention is a nether garment of substantially the configuration and representation shown in the accompanying drawing.

15 In the drawing, *a* represents the tubular portion for receiving the trunk of the body, and *b* the tubular leg portions.

The essential feature of the design resides in the shape and configuration of the panel or back portion of the garment. This panel, as shown at *c*, is bordered by the ogee-curved 20 edges *d* *e* and is decorated with the middle inverted-Y-shaped panel *f*.

What I claim is—

The design for an undergarment, substantially as herein shown and described.

JEREMIAH A. SCRIVEN.
